REMOVABLE SEAT AND BACK UNITS FOR
UPHOLSTERED FURNITURE

Stanley J. Kostrowski, Jersey City, N.J.

Application December 8, 1948; Serial No. 64,082

3 Claims. (Cl. 155—180)

1

This invention relates to chairs and more particularly to removable seat and back members for upholstered chairs.

It is an object of this invention to provide an upholstered chair of greater comfort than heretofore possible.

A further object is to decrease the labor required in the manufacture of such furniture.

Another object is to facilitate the repairs of upholstered furniture.

It is also an object of the instant invention to reduce the cost of distribution of furniture.

An additional object is to increase the useful life of upholstered furniture.

Other objects of the instant invention will become apparent in the course of the following specification.

In the accomplishment of these objectives, the inside of the arms of any chair frame designed to be upholstered are first formed and the inside cover of the arms attached as well as the outer covers of the arms and back. In the framework of the back, a removable back member is inserted while in the framework of the seat, a removable seat member is inserted. The removable members are unique in the method of attaching the covers and related members. Rather than using the well known webbing tacked along the edges of the back and seat frameworks, the removable back and seat members are made with individual frames designed to be fitted into corresponding positions of the chair. Along the base of the separate frames are protuberances which, after the burlap and filling and cover are in position over the springs, are designed to be bent over the edges of the burlap and cover holding the same securely in place and making each of the members separable from other parts of the chair. In the case of repairs to the back and seat, where the pointed protuberances have been broken off, a sleeve is provided for slipping over the removable frames and along the bottom surface portions of which new protuberances are provided. Catches along the top of the back framework hold the replaceable back member in position while the removable seat member is suspended by springs in the seat framework.

The invention will appear more clearly from the following detailed description when taken in connection with the accompanying drawing showing, by way of example, a preferred embodiment of the inventive idea.

In the drawings:

Figure 1 is a front elevational view of an upholstered chair partially broken away to show

2

fragmentary portions of the removable back and seat members in place and constructed in accordance with the principles of this invention.

Figure 2 is a sectional view along the line 2—2 of Figure 1.

Figure 3 is an enlarged view of the upper left hand corner of the back unit shown in Figure 1.

Figure 4 is a sectional view along the line 4—4 of Figure 3.

Figure 5 is an enlarged perspective view of the frame of the back and seat units showing how the material is held in place.

Figure 6 is a sectional view along the line 6—6 of Figure 2.

Figure 7 is a sectional view along the line 7—7 of Figure 2.

Figure 8 is a sectional view along the line 8—8 of Figure 6 but on an enlarged scale.

Figure 9 is a sectional view along the line 9—9 of Figure 6 and also on an enlarged scale.

Figure 10 is an enlarged fragmentary view of the frame of the seat unit showing the method of releasably attaching the seat unit to the front of the chair.

Figure 11 is a sectional view along the line 11—11 of Figure 10.

Figure 12 is a perspective view of the replaceable sleeve for the frame of the back and seat units.

Referring now in greater detail to the drawings in which like reference numerals indicate like parts, reference numeral 10 (Figs. 1 and 2) indicates the upholstered chair, 11 the removable back member, and 12 the removable seat member.

The chair 10 is constituted of the upholstered arms 13 and 14 (Fig. 1), the back framework 15 (Fig. 2), and the seat framework 16.

The upholstered arms 13 and 14 are formed in the usual manner.

The back framework 15 is made with the spaced parallel side members 17 and 18 (Figs. 1 and 2), and the spaced parallel top member 19 (Fig. 2) and bottom member 20 which may be joined along corresponding ends in the usual manner.

Within the back framework 15 are the second members 21 and 22 (Figs. 1 and 7) spaced parallel to the side members 17 and 18, extending between the top and bottom members 19 and 20 and substantially in the line of intersection of the plane of the inside surface portions of the arms 13 and 14 extended with the back framework 15. Of course, the positioning of the second members may be varied as desired and even the design of the back framework could be changed.

The back framework 15 is attached to the seat

framework 16, later described, in any known manner and extends upwardly therefrom at the back as illustrated.

Within the back framework 15 previously described, the removable back member 11 is inserted. The removable back member 11 is formed with a frame of angle bars most clearly shown in Figure 5 and in which it will be noted that one edge 23 is turned. In the frame, the turned edge 23 is directed outwardly as shown in Figures 6 and 7 and so positioned to prevent an otherwise sharp edge from excessive wear on the subsequently described burlap and cover. Along the bottom of the non-turned portion of the angle bars is a row of tooth-like protuberances 24 which may be formed integral with the body portion by stamping or otherwise. The protuberances 24 are bendable and are designed to be inserted through the burlap and cover and then turned thereover. One protuberance 24 may be seen in Figure 5 in the unbent position and two in the bent position after having been passed through the burlap and cover.

The angle bars are formed into a frame for the removable back member (Fig. 7) in which there is an upper rectangular portion 25 and a lower rectangular portion 26 separated by the common member 27. The upper rectangular portion 25 is formed with the opposed end members 28 and 29, the top member 30, the common member 27 elongated by the end members 31 and 32 and spaced parallel to the top member 30. While the positioning of the common member 27 and associated end members 31 and 32 in the frame may be varied, it has been found desirable to have the same substantially along the line of intersection of the plane of the top surface portions of the arms 13 and 14 extended with the back framework 15. The common member 27 need not necessarily be an angle bar but the end extensions 31 and 32 are and carry along the bottom surface portions thereof of the previously mentioned protuberances 24. The various members are fastened along corresponding ends by any suitable means.

The lower rectangular portion 26 is made with the common member 27 and the bottom member 33 spaced parallel thereto and the spaced parallel end members 34 and 35 which are secured along corresponding ends in a known manner.

The top member 30 of the upper rectangular portion 25 is releasably attached to the top member of the back framework 19 by the catches 36, 37, and 38 which are illustrated in Figure 4. In this figure it will be noted that the nonturned portion of the angle bar with the burlap and cover secured by the protuberances 24 is releasably slid between the catch and the outside surface portion of the top member 19. Somewhat similar catches 39 and 40 are disposed on the second members 21 and 22 for the releasable support of the common member 27. As shown in Figure 7, the spaced parallel side members 28 and 29 of the upper rectangular portion 25 are supported by the upper part of the spaced parallel side members 17 and 18 of the back framework 15 while the spaced parallel side members 34 and 35 of the lower rectangular portion 26 are supported by the lower part of the second members 21 and 22 of the back framework 15. Intermediate the spaced parallel side members of the removable frame are the spaced parallel supports 41, 42, and 43 upon which the known spring members 44 are mounted in a known manner. The spring members 44 may be fastened together at the top 70

in a known manner to maintain the same in a proper position.

The seat framework 16 (Fig. 2) is made with the spaced parallel side members 45 and 46 (Fig. 6), and the front member 47 spaced parallel to the back member 48, said members being secured along corresponding ends in a known manner.

Within the seat framework 16 is the removable seat unit 12 also formed of the angle bars previously described and constituted of the opposed side members 49 and 50, the front member 51 in opposed relationship to the back member 52. The length of the members 49, 50, 51, and 52 is less than the length of the corresponding members of the seat framework so that the removable seat can be substantially inserted therein. The various members are attached as desired along corresponding ends and the side members 49 and 50 flare upwardly and outwardly at the front as best seen in Figures 2 and 9 to compensate for the variation in elevation of the upper edge of the front member 47 compared with the points of attachment 53a (Fig. 2) along the back of the seat framework 16 (Fig. 2). Along the front member 51 of the frame of the seat unit 16 are the similar key openings 53 which are removably attached over the screws 54 as shown in Figure 10. Within the frame of the seat unit 16 are the spaced parallel spring supports 55, 56, 57, and 58, similar to the previously described spring supports 41, 42, and 43 for the removable back member 11, which support the springs 59 interconnected in the plane of the top portions thereof in any known manner. Spring members 60 support the sides of the frame within the seat framework as shown. In addition, suspension springs 61 (Fig. 2) under tension are connected between the bottom member 33 of the removable back member and the removable back member 52 of the removable seat unit 12 as shown in Figures 2 and 6.

The operation is as follows:

A chair frame is first made in the usual manner. The removable back and seat members with the springs attached or otherwise are then made by the spring manufacturer ready for the filling and covers which are attached by virtue of the protuberances 24 eliminating the use of tacks and webbing. Manufactured paddings as now supplied are ideal for this method of manufacture and there is no need for special or extra reinforcements or frames as now required for some types of springs. The tops of the springs may be secured in the usual manner after which the burlap member 62 (Fig. 5) and the cover 63 are inserted with the filling therebetween as desired and the edges of the burlap 62 and cover 63 inserted over the open protuberances 24 which are then bent over the outside surface portion of the cover as shown in Figure 5. The removable back member 11 is then inserted in the back framework with the flat surface portion of the angle bar forming the spaced parallel top member 30 inserted in the catches 36, 37, and 38, and the common member 27 in the catches 39 and 40. To hold the back member 11 down tightly on the catches, one or more springs 61 (Fig. 2) are connected between the bottom of the removable back member 11 and the back of the removable seat member 12. The removable seat member 12 is next inserted with the key openings 53 in the spaced parallel front member 51 over the screws 54 after which the springs 60 are attached between corresponding side and back members of the seat frame work and removable unit as shown.

By this arrangement, sagging bottoms are eliminated, extra spring action given the seat for added comfort, and the life of the seat member substantially increased. Moreover, by this arrangement, show room space is saved because one chair can be equipped with different removable back and seat members the better to show how the chair will look with different treatments. If and when the removable back and seat members need repair, the work may be accomplished without removing the chair from the premises. If when making repairs, the protuberances 24 are lost, the sleeve 62a (Fig. 12), is slipped over the base portion of the angle bar to supply new protuberances 24.

Of course, a rubber top may be used in place of the springs and filling and the support bars for the springs or rubber may be run in two directions (not shown) and laced or riveted where crossed.

It is apparent that the specific illustrations shown above have been given by way of illustration and not by way of limitation and that the structures shown above are subject to wide variation and modification without departing from the scope or intent of the present invention. All of such variations and modifications are to be included within the scope of the present invention.

What is claimed is:

1. In a chair having upholstered arms, back and seat frameworks, the back framework having spaced top and bottom and side members, the side members being constricted between the upholstered arms; a removable upholstered back for the back framework in combination with a removable upholstered seat for the seat framework, the removable back comprising a frame of angle irons, the frame having spaced top and bottom members and side members coacting with corresponding members of the rear framework, one side of the angle irons being in the plane of the back framework and the other side extending forwardly thereof along the outer periphery of the angle iron frame, the side of the angle irons in the plane of the back framework having rearwardly directed protuberances formed thereon, spring supports disposed between the top and bottom members of the angle iron frame and one spring support between the side members at the points of constriction, a catch disposed at both ends of the top member of the back framework coacting with the top member of the angle iron frame, a catch disposed on both side members of the back framework substantially at the points of constriction and coacting with the spring support between the side members of the angle iron frame, a cover disposed over the springs and removably secured by the protuberances on the angle irons, and spring tension means between the bottom member of the angle iron frame and the removable seat and between the removable seat and the seat framework.

2. In a chair having upholstered arms, back and seat frameworks, the seat framework having spaced front and back and side members; a removable upholstered seat for the seat framework in combination with a removable upholstered back for the back framework, the removable seat comprising a frame of angle irons, the frame comprising spaced front and back and side members, the side members extending upwardly and forwardly at the front, means releasably securing

the front member of the angle iron frame to the top of the front member of the seat framework, the side and back members of the angle iron frame being spaced from the corresponding members of the seat framework, one side of the angle irons being substantially in a plane parallel to the plane of the seat framework and the other side at 90° thereto and extending outwardly around the outer periphery of the frame, the bottom surface of the angle irons in the plane of the seat framework having downwardly directed protuberances formed thereon, spaced spring supports disposed between the side members of the angle iron frame, springs disposed on the supports and extending upwardly therefrom, a cover over the springs and angle iron frame removably secured by the protuberances, and spring tension means disposed between the side and back members of the angle iron frame and the corresponding members of the seat framework and between the angle iron frame of the removable seat and the removable back for the back framework.

3. In a chair having upholstered arms and a rigid back and seat framework, the seat framework having spaced parallel front and back members and spaced parallel side members disposed intermediate the corresponding ends of the front and back members and the back framework extending upwardly from the back member of the seat framework; the improvements comprising a removable upholstered seat for the seat framework in combination with a removable upholstered back for the back framework, the removable upholstered seat comprising spaced parallel front and back members and spaced parallel side members disposed intermediate the corresponding ends of the front and back members, said members having a length less than that of the corresponding members of the seat framework, spring tension means for removably securing the side members and the back member of the upholstered seat to the corresponding members of the seat framework with the front member of the upholstered seat superposed on and releasably secured to the front member of the seat framework, means for removably securing the upholstered back to the back framework intermediate the upholstered arms, and spring tension means for releasably securing the back member of the upholstered seat to the bottom of the upholstered back.
